SAFETY ATTACHMENT FOR POCKETS

Charles J. Pokora, Milwaukee, Wis.

Application November 6, 1933, Serial No. 696,821

5 Claims. (Cl. 2-250)

This invention pertains to a safety attachment for pockets, and more particularly for garment pockets utilized for watches, wallets, and other articles:

5 The invention has primarily for its object to provide an exceedingly simple and inexpensive device, which can be quickly and easily attached to any garment pocket to prevent either accidental or undesired removal of its contents.

10 Incidental to the foregoing, a more specific object resides in the provision of an attachment for resiliently restricting the pocket opening, whereby articles may be readily inserted or removed when desired, and yet retained against accidental or undesired removal.

15 A still further object resides in the novel manner of attaching the device to a pocket, whereby sewing and unsightly mutilation of the fabric or garment is eliminated.

20 Lastly, it is an object to provide novel means for inserting the resilient or elastic member through the fabric, and subsequently locking the same against accidental displacement.

With the above and other objects in view, which will appear as the description proceeds, the invention resides in the novel construction, combination and arrangement of parts, substantially as hereinafter described and more particularly defined by the appended claims, it being understood that such changes in the precise embodiment of the herein disclosed invention may be made as come within the scope of the claims.

25 In the accompanying drawing is illustrated one complete example of the physical embodiment of the present invention constructed according to the best mode so far devised for the practical application of the principles thereof.

In the drawing:—

Figure 1 is a fragmentary elevation of a garment with the present invention applied to the pocket contained therein.

Figure 2 is a detail section taken on the line 2—2 of Figure 1, illustrating the manner in which an article is inserted or removed from the pocket.

40 Figure 3 is a similar section, illustrating the manner in which the pocket is normally restricted by the use of the present invention.

Figure 4 is an elevation of one of the attaching buttons to which the resilient connecting member is secured.

45 Figure 5 is an illustration of the detachable button for securing the attachment to the pocket.

Figure 6 is a fragmentary detail illustrating the manner in which the resilient connecting member is threaded through the detachable button.

Figure 7 is a detailed section, taken on the line 7—7 of Figure 1, further illustrating attachment of the invention to a pocket, and

Figure 8 is a similar view illustrating the completion of attachment.

5 Referring now more particularly to the accompanying drawing, the numeral 1 designates the garment, which, in the present instances, comprises a pair of trousers provided with a conventional watch pocket 2 adjacent the usual 10 waistband 3 of the trousers. In accordance with established practise, the outer fabric of the garment is provided with a stitched opening 4, with which the pocket 2 communicates, the pocket comprising inner and outer walls 5 and 6, respectively, formed from blanks of fabric stitched together along their marginal edges.

15 As stated in the objects, the present invention is directed to an attachment for resiliently restricting the opening 4 of the pocket 2, and while this may be accomplished in various ways, an exceedingly simple structure has been illustrated, in which a conventional button 7 is utilized, and has secured thereto in any suitable manner an elastic or resilient band 8, which in the present 25 instance is looped through the usual openings in the button 7.

20 In attaching the invention, the resilient band 8 is threaded through the outer fabric of a garment and the walls of the pocket 2, as best illustrated in Figure 7, and, as shown in Figure 1, the device is attached to the pocket intermediate its side edges, to restrict the opening 4 to the desired width for accommodating the article to be carried in the pocket. To facilitate the attaching 30 operation, and eliminate the necessity of sewing; or mutilating the fabric of the garment and pocket, an exceedingly simple and novel threading device is provided, which comprises a combination clasp and needle 9, formed from a piece 35 of wire, having its ends bent back upon itself to provide spaced loops 10 and 11, respectively.

30 Here it will be noted that the ends of the wire are bent transversely of the loops, thus eliminating points and sharp edges, which would naturally catch in the fabric and obstruct the passage 45 of the clasp through the fabric.

40 After the clasp has been forced through the fabric, a detachable button is threaded over the clasp, it being noted that the button 12 is provided with an elongated opening 13 to permit passage of the loops. The flexible band, which is carried by the loop 11, is then drawn through the button 12, after which the loop 11 is turned 50 toward the face of the button 12, and seated in 55

an elongated groove 14, which transversely intersects the opening 13. The loop 10 is then broken off, which operation is facilitated by an indenture or mutilation 15 provided in the clasp intermediate loops 10 and 11. Thus the loop 11 is securely retained against longitudinal movement in the groove or space, 14, and serves to securely connect the resilient band 8 with the button 12.

In operation, when it is desired to insert an article into the pocket 2, such as a watch, as illustrated, it will be readily appreciated that the resilient band 8, which normally forms a restriction in the pocket, will yield, permitting the watch to pass the same, after which it draws the walls of the pocket together, as illustrated in Figure 3, and serves to prevent malicious or accidental removal of the watch, thus not only defeating pick-pockets but also prevent accidental displacement of the watch or article from the pocket, which frequently occurs when the wearer of the garment bends over, or unintentionally turns the garment upside down in removing the same.

From the foregoing explanation, considered in connection with the accompanying drawing, it will be readily seen that an exceedingly simple and inexpensive device has been provided for quick and easy attachment to any pocket, without stitching or mutilating the same. Heretofore various safety clasps have been provided, but practically all of these are expensive and require some form of connection to the article itself, which makes it awkward and inconvenient to insert or remove the article from a pocket, which is frequently required, particularly in changing garments.

It will be further appreciated that while the invention requires no manipulation in serving its function to restrict the opening of the pocket and retain the articles therein, the same can be easily removed for any desired purpose, although securely attached against accidental displacement.

While the drawing illustrates a wire needle (Figure 6), it is obvious that I may, without departing from the spirit of the invention, substitute for the wire element a pressed element, either in the form of metal or other rigid sub-

stance, for accomplishing the same result. Also in this connection I have minutely described the button element, which element may be varied in accordance with the claims.

I claim:—

1. In combination with a normally flat pocket having yieldable front and rear walls secured together at their side and bottom edges, an elastic member passing transversely through the walls of the pocket to restrict its opening. 5

2. In combination with a normally flat pocket having yieldable front and rear walls secured together at their side and bottom edges, an elastic member passing transversely through the walls of the pocket to restrict its opening, and means 10 for detachably securing said member to the pocket.

3. In combination with a normally flat pocket having yieldable front and rear walls secured together at their side and bottom edges, a button, 20 an elastic member passing transversely through the walls of the pocket and having one end secured to said button, and a second button detachably secured to the opposite end of said elastic member for securing the same to the pocket. 25

4. In combination with a pocket, an elastic member passing transversely through the walls of the pocket to restrict its opening, a button for anchoring one end of said band, a second button for attachment to the opposite end of 30 said band, and means for threading said resilient member through the walls of the pocket and detachably securing the same to said second button.

5. In combination with a pocket, an elastic member passing transversely through the walls of the pocket to restrict its opening, a button for anchoring one end of said band, a threading member comprising a wire having its ends bent back upon itself to form spaced loops and being mutilated intermediate its bent ends to permit 40 severing said loops, one of said loops receiving said resilient member, and a second button provided with an elongated opening and a transverse groove intersecting said opening for reception of the loop which carries said band. 35
